LAMINATED CONTAINER

David C. Shepard, St. Paul, Minn.

Application March 2, 1933, Serial No. 659,271

10 Claims. (Cl. 229—5.5)

My invention relates to laminated containers and has for its object to provide a container constructed of sheets of material adapted to be secured together to form a combined wall and bottom structure capable of effectively resisting the stresses to which containers are usually subjected.

Another object of the invention resides in providing a container in which the bottom is secured to the wall structure of the container in such a manner that the stresses to which the container is subjected will not cause the bottom to be disengaged or loosened from the wall structure.

An object of the invention resides in constructing the bottom with a circular body portion adapted to extend across the lower end of the wall structure of the container and to form the said body portion from sheets of paper having tongues at the edge of the body portion adapted to be bent upwardly therefrom and to be secured to the inner surface of the wall structure of the container.

A still further object of the invention resides in arranging said tongues so that the tips thereof are disposed at a higher elevation than the body portion of the bottom.

An object of the invention resides in constructing the wall structure of sheets of flexible material arranged in laminations with the lower marginal portions of the laminations bent back upon and secured to the under side of the body portion of the bottom.

Another object of the invention resides in providing a ring extending about the bottom at the periphery thereof and disposed between the bottom and wall structure of the container.

A still further object of the invention resides in imbedding said ring within the body portion of the bottom.

An object of the invention resides in constructing the body portion of the bottom of sheets of flexible material and in disposing said ring in between certain of said sheets.

A feature of the invention resides in disposing said ring between the outermost sheet of the bottom and the next to the outermost sheet thereof.

An object of the invention resides in constructing the bottom so that the body portion thereof forms a reentrant angle with respect to the wall structure of the container and in utilizing a ring of triangular cross-section disposed within said reentrant angle.

A still further object of the invention resides in constructing the wall structure of the container of sheets of flexible material arranged in

laminations with the marginal lower ends of the laminations folded about said ring and secured to one another and to the under surface of said bottom structure.

Other objects of the invention reside in the novel combination and arrangement of parts and in the details of construction hereinafter illustrated and/or described.

In the drawings:

Fig. 1 is a perspective view of a container constructed in accordance with my invention. 10

Fig. 2 is a developed view of an unformed bottom illustrating the manner of arranging the sheets from which the bottom is constructed and showing the last applied sheet in dotted lines. 15

Fig. 3 is a diametral sectional view taken through the bottom structure and showing the method of assembling the reinforcing ring and the sheets forming the body portion of the bottom. 20

Fig. 4 is a perspective view of the bottom after the same has been formed and prior to the application of the wall structure thereto. 25

Fig. 5 is a sectional detail view taken on line 5—5 of Fig. 1.

In the construction of laminated containers and particularly paper containers with inset bottoms it has heretofore been the custom to form flanges on the bottom structure depending therefrom and to secure said flanges to the lowermost portion of the wall structure of the container in various different ways. Such construction permits of the bottom being forced away from the wall structure when considerable load is carried by the container and when the container receives the usual stresses to which containers are subjected. The present invention provides a container in which such disadvantages are entirely eliminated and which is procured through the extending of the flange on the bottom upwardly along the walls of the container and in directly securing the same to the inner surface of the wall structure of the container. 35

In Fig. 1 I have shown a container which is indicated in its entirety at A and which is particularly adapted to be used for shipping butter and similar commodities. This container comprises a wall structure 10 in the shape of a frustum of a cone which is open at its upper end as indicated at 11 and which is provided at its lower end with a bottom 12 (Fig. 5). At the upper open end 11 of the container is provided a hoop 31 which encircles the free end of the wall structure 10 and which stiffens and reinforces the 40

5 container at such locality. A bead 21 disposed at the lower end of the container serves to stiffen and reinforce the same and assists in attaching the wall structure to the bottom of the container. 10 The various parts forming the container A and the method of constructing and assembling the same will now be described in detail.

15 The bottom 12 is constructed to provide a circular body portion 14, dished as indicated at 20, 10 which body portion is adapted to fit into the interior of the lowermost end of the wall structure 10 of the container and to close the same and is further constructed with a flange 15 extending upwardly from said body portion. This flange is 15 feathered at the free edge 16 thereof for a purpose to be presently described in detail.

20 The bottom 12 is constructed from a number of sheets of some suitable flexible material 13 such as paper or the like, best shown in Fig. 2. 20 These sheets are all square in form and are of a width somewhat greater than the diameter of the circular body portion 14 so that said sheets provide a band 17 which forms a part of the flange 15 and which is of a thickness equal to 25 the thickness of all of the sheets of paper.

25 In assembling the parts of the bottom, glue is applied between the sheets 13 and each sheet angularly disposed with respect to the previously applied sheet. This causes the corners 18 of the 30 sheets to become distributed throughout the circumference of the bottom structure. By selecting the proper angle of rotation, uniform distribution of the corners results. Where six sheets are used, the angle between like diagonals of 35 adjacent sheets would be fifteen degrees. Due to the fact that the sheets of paper are square the corners 18 thereof become spaced from one another at the extreme marginal portions of the sheet. Inwardly thereof the said corners overlap 40 each other, the amount of overlap increasing toward the lower periphery and flange so that the portion of the flange where the same issues from the body portion 14 is of the same thickness as said body portion and feathers to the thickness of 45 a single sheet of paper at the free edge thereof.

50 For the purpose of constructing the bead 21, a ring 22 is employed which is substantially triangular in cross section and which is of an exterior diameter such that the same fits snugly within 55 the interior of the wall structure 10 of the container. This ring may be constructed of metal, wood, reed, fibre or any other suitable material and in addition to stiffening and reinforcing the lowermost edge of the container, forms a core upon which the marginal lower end of the wall 60 structure of the container may be wrapped when the same are constructed to form the bead 21.

65 In the formation of the bottom 12, the sheets are assembled as shown in Fig. 2 with the exception of the sheet 23 which is omitted and glue applied in between the various sheets. The ring 22 is then placed against the next to the last of the sheets 13 and the sheet 23 applied to the outer edge of said ring. The arrangement of the sheets when so applied is shown in Fig. 3 which 70 illustrates the sheet 23 as undermost with the ring resting upon the same and the remaining sheets resting upon the ring. While the sheets 13 and ring 22 are so disposed, the same are pressed in suitable dies which forms the flange 15 and the body portion 14 causing the flange to extend upwardly from the body portion. Through the shape of the die the body portion 14 of the bottom is formed dished as shown at 75 20 and is constructed with a rounded corner 25

5 at the juncture between said body portion 14 and flange 15. Due to the construction of the dies the sheet 23 is securely glued to the undermost of the sheets 13 within ring 22 and is also caused to be wrapped about the ring 22, the corners 25 10 of said sheet extending upwardly of the ring 22 and being glued to the corresponding corners 18 of the other sheets. In this manner, ring 22 becomes imbedded between certain of the sheets of the bottom 20 which holds the said ring in position and while the wall structure 10 is being formed and applied to the bottom structure.

15 In the construction of the container the bottom 14 is placed against the end of a mandrel, not shown, which is constructed upon the end thereof to receive the flange 15 and to fit along said flange and into the corners 25 and the dished portion 20 of the bottom structure. While so disposed the bottom is temporarily held supported against the mandrel through any suitable device 20 which bears against said bottom structure and permits of the rotation of the mandrel. With the bottom so supported and the flange 15 fitting snugly upon the exterior surface of the mandrel, the wall structure is formed and built upon the 25 mandrel and secured to the bottom structure. This is accomplished as follows: Sheets of flexible material such as paper or the like indicated at 27 and segmental in form and of proper curvature, are glued one upon the other with extreme 30 marginal portions 28 projecting outwardly beyond the ring 22. As the various sheets are applied, the marginal portions 28 thereof are turned back and about the ring 22 and secured to the body portion 14 of the bottom 20 or to the previously applied sheet as the case may be. By means of this construction, the bead 21 is formed and the same securely attached to the bottom structure. It will readily become apparent that ring 22 is firmly retained between the bottom 20 40 and the wall structure 10. Due to the formation of the bottom 20 with the curved corner 25 upon the interior thereof, a curved portion is produced on the exterior of the bottom structure which forms in conjunction with the wall structure a 45 reentrant angle 29. Ring 22 being triangular in cross section, is provided with a portion 30 which fits into the reentrant angle 29 and completely fills up the space formed between the bottom and wall structure of the container. When the end 50 portions 28 of sheets 27 are properly applied, ring 22 is completely enclosed and firmly imbedded in the structure of the container.

55 In the construction of the container the bottom 20 may be first formed and allowed to dry and the wall structure 10 thereafter formed and applied to the body structure as previously described. In such case when the wall structure dries, the same contracts and firmly grips the bottom structure making an extremely tight and 60 rigid construction. If desired, however, the wall structure may be constructed shortly after the formation of the bottom and all parts of the container allowed to dry and cure at the same time.

65 To facilitate the gluing of the first of the sheets 27 to the flange 15, a liner may be employed which is first placed upon the mandrel and to which the corners 18 of the flange 15 are glued. Glue may then be applied to this liner 70 and the sheets 27 wrapped about the mandrel and about the previously applied portion of the container and the method proceeded with as previously described. Such liner may be of the full height of the receptacle or only as high as the 75

flange 15, and several sheets may also be used in the construction thereof.

Due to the construction of the bottom 12 with the dished portion 14 and the bead 21 the container receives support both at the marginal portion thereof and at the center of the bottom. In this manner the weight contained within the container is more uniformly distributed so that the entire load is not entirely carried by the joint between the bottom and wall structure of the container. At the same time a construction is formed by means of which the bottom may be readily grasped through engagement with the bead 21 permitting of readily handling the container when the same is used in the ordinary manner.

My invention is highly advantageous in that an extremely simple and practical container is provided in which waste of material is reduced to a minimum and in which strength and rigidity are exceedingly great. With my container it becomes practically impossible to pry apart or loosen the bottom of the wall structure from the container regardless of the load carried by the container and the usage given the same. Due to the fact that a bead is used instead of the conventional flange employed in similar containers, a far stronger container is provided and battering down of the flange or marginal portion of the container at the lower edge thereof entirely prevented. The reinforcing ring constituting the core on which the bead is formed also stiffens and reinforces the entire container structure preventing collapse of the container when roughly handled and preventing the tearing apart of the bottom and wall structure and the distortion or crushing of the rim of the same. My improved container can be constructed in an easy and expeditious manner and can be built at an exceedingly low cost with very little waste of material. With my container an absolutely tight joint is formed between the bottom and wall structure so that leakage through the same is entirely prevented.

Changes in the specific form of my invention, as herein disclosed, may be made within the scope of what is claimed without departing from the spirit of my invention.

Having described my invention, what I claim as new and desire to protect by Letters Patent is:

1. In a circular container having a wall structure, a bottom therefor constructed of square sheets secured together and disposed one upon the other and progressively rotated with respect to each other to uniformly distribute the corners of the sheets about the periphery of the bottom, said sheets being arranged to provide a circular body portion fitting into the lower end of the wall structure, the corners of said sheets being turned upwardly from the body portion of the bottom and secured to the inner surface of the wall structure.

2. In a circular container having a wall structure formed with laminations, a bottom therefor constructed of square sheets secured together and disposed one upon the other and progressively rotated with respect to each other to uniformly distribute the corners of the sheets about the periphery of the bottom, said sheets being formed to provide a circular body portion adapted to fit within the lowermost portion of the wall structure, the corners of the sheets of said bottom being bent upwardly and secured to the inner surface of the wall structure of the container, the marginal lower ends of the laminations of the

wall structure being bent about the under surface of the bottom and secured thereto and to one another.

3. In a circular container having a wall structure, a bottom therefor having a body portion adapted to extend across the lower end of said wall structure, a ring imbedded within said bottom, the lower end of said wall structure extending about said ring and being secured to the under surface of the body portion of said bottom.

4. In a circular container having a wall structure formed with laminations, a bottom therefor comprising a body portion adapted to extend across the lower end of said wall structure, a ring imbedded in the body portion of said bottom, the marginal lower ends of the laminations of the wall structure being bent about the ring and secured to the under surface of said bottom.

5. In a circular container having a wall structure, a bottom therefor constructed of sheets secured together and disposed one upon the other to provide a body portion adapted to extend across the lower end of the wall structure, and a ring imbedded in said body portion and disposed between certain of the sheets thereof.

6. In a circular container having a wall structure, a bottom therefor constructed of sheets secured together and disposed one upon the other to provide a body portion adapted to extend across the lower end of the wall structure, and a ring imbedded in said body portion and disposed between the lowermost sheet and the next to the lowermost sheet of said bottom.

7. In a circular container having a wall structure, a bottom therefor constructed of sheets secured together and disposed one upon the other to provide a body portion adapted to extend across the lower end of the wall structure, said sheets being constructed with tongues extending upwardly from the body portion of the wall structure at the margin thereof, a ring mounted upon said body portion and extending about the same at the marginal portion thereof and another sheet secured to the lowermost of the first-named sheets and enveloping said ring, said last-named sheet having tongues issuing upwardly from said ring and secured to some of the tongues of the other of the sheets, said tongues being secured to said wall structure.

8. In a circular container having a wall structure, a bottom therefor constructed of sheets secured together and disposed one upon the other to provide a body portion adapted to extend across the lower end of said wall structure, said sheets being provided at the edge of said body portion with tongues adapted to be bent upwardly from the body portion and to be secured to said wall structure, said bottom and wall structure forming an angular groove and a ring of angular cross-section disposed within said groove of said container and filling the same.

9. In a circular container having a wall structure, a bottom therefor constructed of sheets secured together and disposed one upon the other to provide a body portion adapted to extend across the lower end of said wall structure, said sheets being provided at the edge of said body portion with tongues adapted to be bent upwardly from the body portion and to be secured to said wall structure, said bottom forming a re-entrant angle with respect to said wall structure and a ring of triangular cross-section disposed within said reentrant angle of said container, the

lowermost marginal portion of said wall structure extending about said ring and being secured to the under surface of said bottom.

10. In a circular container having a wall structure formed with laminations, a bottom therefor constructed of sheets secured together and disposed one upon the other to provide a body portion adapted to extend across the lower end of the wall structure, said sheets being formed with tongues at the edges of the body portion

adapted to be bent upwardly therefrom and secured to the inner surface of the wall structure, said bottom forming in conjunction with said wall structure a reentrant angle, a ring of triangular cross section disposed within said reentrant angle, the marginal lower ends of the laminations of the wall structure being bent about said ring and secured to the under surface of the body portion of the bottom.

DAVID C. SHEPARD. 10
